JOHN W. HOGUE, OF SPRINGFIELD, VERMONT, ASSIGNOR TO PARKS & WOOLSON MACHINE COMPANY, OF SPRINGFIELD, VERMONT, A CORPORATION OF VERMONT.

TRADE-MARKING MACHINE.

1,181,596.

Specification of Letters Patent. Patented May 2, 1916.

Application filed July 26, 1913. Serial No. 781,295.

To all whom it may concern:

Be it known that I, JOHN W. HOGUE, citizen of the United States, and resident of Springfield, county of Windsor, State of 5 Vermont, have invented certain new and useful Improvements in Trade-Marking Machines, of which the following is a specification.

This invention relates to machines for 10 stamping or marking with ink, cloth or other fabric and is intended to provide an efficient and reliable device which may be applied to batching machines or other machines through which the cloth or fabric 15 to be marked is drawn or fed.

In its general features the invention comprises in combination with a marking die or type member, a hollow casing or ink reservoir closed except for a small slot to be 20 traversed by the movable die and having an inking pad arranged in immediate proximity to said slot, in position to form a contact with said die before the die is moved into contact with the fabric to be marked, 25 one object being to prevent the evaporation or drying of the ink. This and other features of the invention will be particularly described in the following specification, and will be defined in the claims annexed hereto. 30 In the accompanying drawings I have illustrated the preferred mode of embodying the principles of this invention.

Figure 1 is a side elevation of the trade-marking device shown applied to so much 35 of a batching machine as is necessary to understand the operation of the invention; Fig. 2 is a front elevation of the same; Fig. 3 is a central vertical section through the ink reservoir and its inking members; and 40 Fig. 4 is a transverse vertical section on the plane indicated by broken line 4-4 of Fig. 3.

In practice this machine is made in the 45 form of a removable attachment that may be applied to various kinds of machines through which the fabric to be stamped is usually passed, such for example as a batching or cloth rolling machine. In this connection I have shown merely the cloth feeding roll a and a portion of the framework a' of such a batching machine adjacent to the point where the trade-marking mechanism is attached.

The trade-marking mechanism embraces 50 a movable and preferably a revolving die

or type member b , which is detachably secured to a revolving gear b' which is driven from the gear a^2 of the cloth roll a or by any suitable means that coördinates the movement of the die b with the travel of the cloth so that the die may be brought into contact, preferably a rolling contact, with the cloth at the same rate of speed as the travel of the cloth, so that the cloth and the die may move in unison during their period of contact. Adjacent to the periphery of the circle described by the die b is arranged the ink reservoir which contains the ink-applying mechanism by which the die is supplied with ink in properly regulated quantities.

The ink reservoir comprises a hollow closed shell c provided with a large circular opening at one end which is normally closed by the plate or closure c' which is held 60 snugly but detachably in position by the retaining bolt c^2 . The opposite end of the casing is provided with a slot c^3 normally closed by a bracket plate c^4 , from which projects inwardly a fixed pintle c^5 which forms 65 an adjustable journal for the rotating ink-carrying cylinder c^6 . This plate or bracket c^4 is pivotally clamped to the adjacent end of the ink well, as indicated at c' , and is adjusted vertically by means of the adjusting 70 screw c^8 tapped into the bottom of the shell c , and engaging a projecting arm of the bracket c^4 .

The ink pad from which the die receives 75 its ink is in the form of a rotary roll d whose supporting end is journaled in a cylindrical bore formed at d' in the shell c . The inking portion of the roll is preferably 80 encircled with a sleeve or pad d^2 of felt or other suitable ink-retaining material, which 85 is held in place by means of a sort of washer d^3 and end screw d^4 . At d^5 the roll is formed with gear teeth, which engage gear teeth c^{10} on the ink-carrying roll, in order to drive 90 the latter roll. The pad roll d itself is 95 driven by a pinion d^6 which intermeshes with the gear b' , the parts being so proportioned and arranged that the surface of the pad roll or ink-applying member moves at the 100 same surface speed as that of the die b , so that the two members may travel in unison 105 while they are in contact.

To avoid the seepage or leakage of ink 110 through the pad roll bearing d' , this portion of the pad roll is formed with an an-

nular groove, as shown at d^{10} , which registers with a slot or opening in the bottom of the bearing, as indicated at d^{11} , so that the ink on reaching this point will naturally flow through the opening d^{11} and fall into the bottom of the reservoir or shell.

- The ink-applying roll or pad d is set as close as practicable to the periphery of the shell at the side where the die passes by it, 10 the wall of the shell being made very thin at this point and being provided with a short peripheral slot, as shown at d^{12} , through which the die passes at each revolution. The ink may be applied through a 15 suitable orifice e , which may be closed by a plug or cap. Only the lower portion of the shell is filled with the ink which is carried by the gear-roll c^s in a thin film into contact with the pad, which in turn applies the ink 20 directly to the marking die b . Both internal rolls may be removed or replaced through the large orifice which is normally closed by the plate c' . The adjustment of 25 the journal c^s serves to give the proper pressure or contact between the two rolls.

The shell c is provided with perforated ears or lugs f by which it is detachably secured to a supporting bracket f^2 by suitable fastening bolts, so that the shell may be removed and replaced by another shell when 30 it is desired to change the color of the ink or for any other reason.

What I claim is:—

1. A hollow casing or shell provided with 35 openings at its opposite ends, a removable closure for each opening, one of said closures being provided with an inwardly extending pin projecting into the interior of the casing to support an ink-carrying roll, 40 a revolving pad mounted above said roll adjacent to a slot formed in the upper wall of said shell, an external set screw having operative connection with said pintle to adjust the same toward or away from the pad 45 and means for causing said rolls to rotate in unison, substantially as described.
2. In a machine for trade marking cloth the combination with the revolving cloth roll, 50 a revolving marking die arranged to mark the cloth at each revolution, a closed ink reservoir provided with a revolving inking pad whose periphery is exposed to contact with

the revolving die through a slot in the reservoir and interconnecting gearing by which the pad, the cloth roll, and the die are rotated at the same surface speed. 55

3. In a cloth marking machine the combination of the marking die mounted on a revolving member, a hollow closed ink reservoir arranged adjacent to the circular path 60 of the die's travel and slotted on one side, a revolving inking pad inclosed in said reservoir close to said slot to contact with said die at each revolution thereof, a driving pinion intermeshing with a gear on the revolving member and proportioned to cause 65 the pad to rotate at the same surface speed as the die, an ink supplying roll inclosed in the reservoir in contact with said pad, and a pinion secured thereto and intermeshing 70 with the pad pinion to cause said roll and said pinion to rotate positively in unison, substantially as described.

4. In a machine for trade marking cloth, the combination with the revolving die, of an 75 ink reservoir slotted on one side to admit the die at each revolution, a rotary inking pad inclosed within said reservoir with its surface close to said slot, an ink supplying roll also inclosed within said reservoir to 80 rotate in contact with said pad, and intermeshing pinions secured to the pad and to the roll, respectively, to cause them to rotate positively at the same surface speed substantially as described. 85

5. An inking device for a cloth marking machine embracing a hollow shell slotted on one side to receive a revolving marking die, a rotary inking pad inclosed within said shell close to said slot in position to contact with 90 the die, an ink supplying roll also inclosed within said shell and having a positive gearing connection with said pad to cause its rotation in unison therewith, and adjusting means by which the pressure of contact 95 between the ink roll and the pad may be varied, substantially as described.

In witness whereof, I have subscribed the above specification.

JOHN W. HOGUE.
